Primary Examiner—Lucy Lieberman
Attorney, Agent, or Firm—Abelman, Frayne & Schwab**[57] CLAIM**

The ornamental design for a champagne bottle, as shown and described.

DESCRIPTION

FIG. 1 is a right-side elevation of a champagne bottle; and, FIG. 2 is a left-side elevation of the champagne bottle.

The portions of the bottom, top, front and rear of the champagne bottle that are not shown in the drawings do not form part of the claimed design.

1 Claim, 2 Drawing Sheets*FIG. 1*

FIG. 2
